UNITED STATES PATENT OFFICE.

ERIC LEOPOLD HUGO COSBY, OF TEDDINGTON, ENGLAND.

TOOTHBRUSH.

Application filed September 17, 1925, Serial No. 56,978, and in Great Britain September 17, 1924.

This invention relates to brushes, and more particularly tooth brushes, and the principal object of the same is to provide a brush in which the stock and bristles, together with the means for securing the stock and bristles to the handle, are removable so that the whole can be readily and easily cleaned.

According to my invention I preferably make the handle and hollow back or frame for holding the stock and bristles from a composition in which a strengthening means, which may be in the form of a wire or strip or a frame, is embedded, and I shape one end 15 of the hollow back or frame and one end of the stock which carries the bristles in such manner that the stock may be inserted in the hollow back and be held in the latter by fastening means engaging the stock. I provide the handle with a catch at its free end 20 and with a longitudinal bore leading to the hollow back and also with transverse holes or slots leading to the bore to facilitate cleaning of the bore. The fastening means comprises a wire or strip positioned in the bore 25 along the length of the handle one end of such wire or strip being capable of engaging the stock and the other a catch at the opposite end of the handle to hold the stock in 30 the back or frame.

Instead of making the handle and back of the brush of a composition I may make the handle and back wholly of metal, for example of silver, but in any construction 35 the stock and bristles, as well as the fastening means, are easily removable for cleansing purposes.

My invention will be understood from the following description aided by the annexed 40 drawings in which

Figure 1 is a front view of a tooth brush constructed according to the invention.

Figure 2 is a rear view of the same.

Figure 3 is a longitudinal section on the 45 line 3—3, Figure 1.

Figure 4 is a transverse section on the line 4—4, Figure 1.

Figure 5 is a front view of a metallic frame assembly before being embedded in 50 composition.

Figure 6 is a section on the line 6—6, Figure 7.

Figure 7 is a side elevation, partly in section, of the frame assembly shown in Figures 5 and 6, and

Figure 8 is a transverse section on the line 8—8, Figure 6.

Referring to Figures 1 to 4 of the drawings, 1 designates the handle portion of the brush, which is formed of suitable composition, said handle having at one extremity a back provided with an opening or recess 2 to receive a brush stock 3. The end wall of the recess 2 remote from the handle is preferably rounded, as at 4, and the opposite end wall of said recess is inclined as at 5. However, it will be understood that the opening or recess 2 may be formed with any suitable contour in accordance with the size or shape of the brush desired and the stock to be used therein. The stock 3, which carries the bristles of the brush, is shaped to correspond with the opening or recess 2 but slightly smaller than the latter so as to be received in said opening or recess. 75

In the back (if formed of composition) I embed a wire or metal frame 6 and in the handle I form a longitudinal bore 7 leading from the opening 2 to a rectangular depression 8 formed in the handle adjacent the opposite end of the latter. The depression 8 at its end opposite to the bore 7 is formed with a catch 12. In the bore 7 is positioned a round rod or wire 9 having one end connected to a flat spring steel piece 10 or other 80 spring means which is positioned in the rectangular depression. The spring piece 10 is longer than the depression 8, so that, when in position in said depression with its free end in engagement with the catch 12, it is 85 bowed outwardly. The spring piece 10 has a button or knob 11 by means of which its free end may be manipulated to engage with and disengage from the catch 12, as will be seen in Figure 3. 90

Holes 13 extend through the handle and also a second depression 14 is formed in the handle for cleansing purposes.

In action the rod 9 is pulled back by pulling on the curved piece 10 until the projecting end of the rod 9 is clear of the opening 2 when the stock 3 which is slightly shorter than the opening, can be inserted. The spring is then released when the end of the rod 9 will be projected by the bowed spring 105 piece 10 forward into a hole 15 in the end of the stock 3 and hold the latter firmly in place by engagement of the rod 9 in the hole 15 of the stock 3 and endwise pressure of the spring piece 10 on the rod 9 to cause 110

the curved end of the stock to engage with the curved end 4 of the opening 2.

To remove the stock 3 from the back, the end of the spring 10 is pulled or sprung out 5 of the catch 12 by the button 11 when the spring 10 and rod 9 can be withdrawn from the handle through the depression 8 and the stock 3 can be removed for proper cleaning by flushing with water and a pin or rod can 10 be passed through the holes 13 if necessary to clean same.

Figures 5 to 8, inclusive, show a frame assembly which is convenient and economical from a manufacturing standpoint since the 15 parts thereof may be stamped from a suitable metal and then be coated with, or embedded in, a suitable composition. The brush when constructed with this form of frame embodies the same essential features 20 as shown in Figures 1 to 4. In this instance the member 6¹, which receives the stock, is preferably stamped from a strip of metal and is substantially rectangular. The ends 16 of the member 6¹ are enclosed in a 25 ferrule 17, a tube 18 to receive the rod 9 having one end inserted in the ferrule being also provided. The ends 16 of the member 6¹, the ferrule 17 and the tube 18 may then be secured by brazing, pressing or other 30 means. The rod or wire 9 is then inserted in the tube 18, the member 6¹ being preferably formed at one end with a lip or flange 19, forming a catch 4^a, and the stock 3 being 35 removably and firmly held within the member 6¹ by engagement of the catch 4^a with one end thereof and the end 15^a of the rod 9 with its other end. The stock 3 is inserted in and removed from the member 6¹ in the same manner as described in connection with Figs. 1, 2, 3 and 4.

It will be understood that various other modifications in the proportions, dimensions and manner of forming the several components of the improved brush may be adopted 45 without departing from the spirit of the invention.

What I do claim as my invention and desire to secure by Letters Patent is:—

1. A tooth brush comprising a handle 50 having at one end a recessed back portion

and having a depression in one of its faces adjacent its other end; said handle also having a longitudinal bore communicating with one end of said recess and with one end of said depression, a rod insertable in said longitudinal bore and having one end projecting into the hollow back portion, a flat spring carried by the opposite end of said rod and adapted to be inserted flatwise in the depression of the handle and having its free end engageable with an end of said depression with its intermediate portion bowed, and a bristle carrying stock adapted to be inserted in the recess of the back portion with one end in engagement with one end of said recess and its other end engaged by said rod.

2. A tooth brush comprising a handle having a recessed back portion, the handle having a longitudinal bore extending partially therethrough and opening into the lower extremity of the recess of the back portion, the handle also having a depression formed in its lower portion thereof, a rod having a flat curved spring portion at one extremity adapted to be inserted in the bore of the handle with the flat curved spring extremity projecting into the depression, a catch formed in the lower extremity of the depression, and a brush stock adapted to be inserted in the recess of the back portion and removably held in position by the other end of said rod.

3. In a tooth brush, a frame of substantially rectangular shape forming a recess to receive a brush stock, a tubular portion, a ferrule fitted over the upper extremity of the tubular portion and in which the lower extremity of the frame is secured, a rod insertable in the tubular handle portion with one end projecting into said recess, a spring carried by the other end of said rod, and a handle and back of composition material in which said frame and tubular portion are embedded, said handle having in one of its faces adjacent its free end a depression to receive said flat spring.

In testimony whereof I have hereunto set my hand.

ERIC LEOPOLD HUGO COSBY.
